METHOD OF AND MEANS FOR BENDING
IRON BARSAnton Wagenbach, Wuppertal-Elberfeld,
GermanyApplication May 27, 1938, Serial No. 210,457
In Germany May 10, 1937

11 Claims. (Cl. 153—45)

Application has been filed in Germany on May 10, 1937.

The known methods of bending iron bars, particularly iron bars for use in reinforced concrete structures, permit only of bending to comparatively small radii, as in these methods the iron has to be bent around a former, for instance a bending pin having the required radius of curvature. If considerable curvatures, that is great bending radii are to be attained, the stationary formers or bending pins become very bulky and heavy and consequently the exchange of such formers is difficult and cannot be carried out by a single operator. For this reason it has been suggested to use, instead of solid formers or bending pins, bending segments having the required length of arc, but this does not solve the difficulties which arise, particularly in the case of radii of considerable size, say several metres, which are now required, particularly in connection with road building.

According to the invention these drawbacks of the known methods are substantially avoided by mounting the iron to be bent between two fixed points and gradually bending the length of iron lying between these fixed points to the required curvature, by means of a curved former having a shape corresponding to the required curvature, the bending taking place not as heretofore from the centre and by pressure, but from a terminal point common to the iron and the curved lever constituting the former, by gradually rolling the curved former upon the iron bar. This method has the advantage that curvatures, such as circular arcs, involutes or other shapes of any desired size can be bent directly without the necessity of employing, as hitherto, very large bending discs or blades and using heavy and unwieldy bending rollers. According to a preferred mode of carrying out the method, the curved former is constituted by a one-armed lever, which is adapted to be clutched to the bending shaft of the bending machine, said shaft constituting at the same time one of the supports for the iron to be bent. The curved bending lever is preferably provided at both ends with an opening for insertion upon the bending shaft, so that it may be selectively used either for right-hand or left-hand curvatures. The other fixed support for the iron to be bent may be constituted by pins adjustably mounted at the ends of the machine table or adjacent projecting members fixed to the table.

The invention is illustrated in the drawing by 55 a constructional example, the drawing showing

a plan of the top of the improved bending machine.

The table plate 1 of the machine is, in known manner, provided with one or more bending discs 2. Upon the end 3 of the main shaft of the bending machine, which projects above the bending disc 2, is fixed a segment-shaped lever 4, which is symmetrically formed and is provided at both ends with a suitable opening 5, so that it may, as indicated by dotted lines, be used also for bending left-hand curvatures. Above the bending lever 4 there is mounted upon the shaft end 3 a clamping yoke 6, the clamping screw 7 of which bears against a pin 8 inserted into the bending disc 2. The pin 8 bears, during the turning of the bending disc 2, against the iron bar x to be bent. The yoke 6 also prevents lifting of the iron bar during the bending. At both ends of the machine table 1 there are provided toothed racks 9 and 10 respectively, each formed with a longitudinal slot 11 for the reception of supporting rollers 12. This arrangement enables the supporting rollers 12 to be fixed in any desired position. The bars 9 and 10 are arranged at the same level as the bending discs 2.

Before commencing the bending operation, the iron rod x is placed in the position indicated by full lines in the drawing. The machine is then set in motion and, due to the rotation of the driving shaft carrying on its end 3 the bending disc 2 and the bending lever 4, the bending lever 4 rolls with its periphery, which has the curvature to be imparted to the iron bar, upon the iron bar, and the latter being supported by the fixed roller 12 and the pin 3, will therefore receive the shape indicated by dotted lines. As soon as the bending lever 4 has reached the end position indicated by dotted lines, the drive of the shaft is stopped in a manner known per se by means of a stop inserted into one of the holes of the bending disc. As indicated by dotted lines, the bending operation may also take place in the opposite direction, whereby a left-hand curvature will be imparted to a bar fixed between the shaft 3 and the supporting roller inserted into the right-hand rack 10. If longer arcs are to be produced than the arc upon the bending lever 4, the above described bending operation may be several times repeated upon the same iron bar, the several bends following each other and constituting one very long bend.

I claim:

1. In a bending machine for bending iron bars, more particularly iron bars for reinforced

55

- concrete structures, the sub-combination of: a table; a bending disc rotatably mounted therein; a shaft for turning said disc having an end projecting upwards from said disc; a curved former adapted to be fixed to said projecting shaft; a clamping yoke fixed to said shaft and also fixed to said disc for holding the bar to be bent; and an adjustable stop upon said table for holding the remote end of the bar.
10. 2. In a bending machine for bending iron bars, more particularly iron bars for reinforced concrete structures, the sub-combination of: a table; a bending disc rotatably mounted therein; a shaft for turning said disc having an end projecting upwards from said disc; a curved former adapted to be fixed to said projecting shaft; a clamping yoke fixed to said shaft and also fixed to said disc for holding the bar to be bent; and an adjustable stop upon said table for holding the remote end of the bar, said adjustable stop being constituted by a transverse member fixed to the table and by a roller adjustably mounted thereon.
15. 3. In a bending machine for bending iron bars, more particularly iron bars for reinforced concrete structures, the sub-combination of: a table; a bending disc rotatably mounted therein; a shaft for carrying and driving said bending disc, said shaft having an end portion projecting upwards from the table and a bending disc; a pin mounted upon said bending disc; a clamping yoke mounted upon the projecting end upon the shaft and having a means for clamping said yoke to said pin; a curved former adapted to be fixed to the top end of said shaft for rotation therewith; and an adjustable stop upon said table; the rod to be bent being located at one point between the top end of the shaft and the pin of the table and supported at the remote end by said adjustable stop.
20. 4. In a bending machine for bending iron bars, more particularly iron bars for reinforced concrete structures, the sub-combination of: a table; a bending disc rotatably mounted therein and having a number of holes for the insertion of a pin; a pin inserted into one of said holes; a shaft for driving said bending disc having an upper end projecting from said disc; a curved former inserted upon said shaft end for rotation therewith; a clamping yoke inserted upon said shaft end and enclosing said pin and having means for clamping to said pin; two bars one at each side of the table, each bar being provided with a slot; and a supporting roller slidably in said slot and fixable therein in any desired position, said curved former being symmetrically shaped and having at either end a hole for fixing to said shaft end.
25. 5. A process for bending iron rods by means of a rocking bending member having a curved rod contacting surface shaped to the bend to be produced in the rod, said process consisting in supporting a rod between two spaced points one of which is adjacent the rocking point of the bending member and the other of which is spaced therefrom, and rocking said member to cause its rod contacting surface to progressively engage
- the rod from the support adjacent the rocking point toward the other supporting point.
6. A process for bending iron rods by means of a rocking bending member having a curved rod contacting surface shaped to the bend to be produced in the rod, said process consisting in supporting a rod between two spaced points one of which is adjacent the rocking point of the bending member and the other of which is spaced therefrom, and rocking said member to cause its rod contacting surface to progressively engage the rod from the support adjacent the rocking point toward the other supporting point, the resistance to bending being progressively increased due to the rolling action of the bending member on the rod.
7. Process for bending iron rods particularly those used in reinforcing concrete by means of an oscillating curved piece, in which first the iron rod is placed between two fixed points and the turning point for the curved piece, and next the part of the iron rod lying between the fixed points is bent outwardly and away from the turning point of the curved piece by means of oscillating the curved piece, whereby the curved piece beginning at one fixed point rolls on the iron rod toward the other fixed point.
8. Process for bending iron rods particularly those used in reinforcing concrete by means of an oscillating curved piece, in which first the iron rod is placed between two fixed points and the turning point of the curved piece, and next the part of the iron rod lying between the fixed points is bent outwardly away from the turning point of the curved piece and rolls on the iron rod beginning at one fixed point toward the other fixed point with increasing lever arm.
9. Process for bending iron rods particularly those used in reinforcing concrete by means of an oscillating curved piece, in which first the iron rod is placed between two fixed supports and a support for the curved piece serving as pivot and next through the oscillations of the curved piece the part of the iron rod lying between the two fixed supports is bent outwardly by the support of curved piece, whereby the curved piece beginning at the one fixed support rolls over the iron rod toward the other fixed support.
10. Process for bending iron rods particularly those used in reinforcing concrete by means of an oscillating curved piece which bends outwardly and away from the pivot point of the curved piece, the iron rod placed between two fixed points and the pivot point of the curved piece.
11. Process for bending iron rods and especially those for reinforcing concrete by means of an oscillating curved piece which bends outwardly and away from the pivot point of said curved piece, the iron rod placed between two fixed points and the pivot point of the curved piece, the use of a curved piece of symmetrical form which has on both ends means for locking on its pivot axis and which starting from one pivot point rolls over the iron rod toward the other fixed point.

ANTON WAGENBACH.
